UNITED STATES PATENT OFFICE.

SAMUEL H. WOLFE, OF LODGEPOLE, NEBRASKA.

LIFTING DEVICE.

1,205,305.

Specification of Letters Patent. Patented Nov. 21, 1916.

Application filed March 28, 1916. Serial No. 87,363.

To all whom it may concern:

Be it known that I, SAMUEL H. WOLFE, a native-born citizen of the United States, residing at Lodgepole, in the county of Cheyenne and State of Nebraska, have invented new and useful Improvements in Lifting Devices, of which the following is a specification.

This invention provides a device for extracting pump rods and pipes from wells, and aims to produce a construction by means of which both the pipe and rods can be simultaneously or independently elevated, and the section or sections of these parts subsequently uncoupled without necessitating the removal of the device from the block and tackle hook, and also eliminating tangling of the rope.

The nature and advantages of the invention will be better understood from the following description when taken in connection with the accompanying drawing, the invention residing in the construction, combination and arrangement of parts as claimed.

In the drawing forming part of this specification like numerals of reference indicate similar parts in the several views and wherein:

Figure 1 is a longitudinal sectional view showing the device in use. Fig. 2 is a sectional view taken on line 2—2 of Fig. 1.

Referring more particularly to the drawing A indicates the pipe made up of a plurality of detachably connected sections, and B the pump rod or like tool desired to be removed.

The device forming the subject matter of the present invention consists of a hollow tubular member 10 which may be of any suitable length, and having arranged therein a bracket 11 which latter preferably includes spaced parallel bars 12, and sockets 13 at the opposite ends of the brackets at which point the said bars are integrally connected. The tubular member 10 adjacent its upper and lower extremities is provided with diametrically opposed alined openings 14 adapted to receive a headed bolt 15 which passes between the spaced bars of the bracket provided to limit the adjustment of the bracket within the tubular member in both directions, and also serving to hold the tubular member and bracket operatively associated. Arranged at the upper end of the

bracket is an eye bolt 16 swiveled within the 55 socket 13, while the lowermost socket of the bracket is interiorly threaded to receive the exteriorly threaded end of the rod 17. This rod projects an appreciable distance below the tubular member 10, and is exteriorly 60 threaded for association with the pump rod or other tool desired to be removed from the well.

In practice the device is supported in vertical position by means of a block and tackle 65 not shown, the hook of which is engaged with the eye bolt 16. The device is then lowered into proper position to permit the lower end of the rod 17 to be coupled with the adjacent end of the pump rod, while the 70 lower extremity of the tubular member 10 is exteriorly threaded for a similar association with the adjacent end of the pipe. With these parts connected, it is manifest that both the pump rods and pipe may be 75 elevated the requisite distance to permit one or more sections of the pipe or pump rod to be uncoupled from the remaining portion of their length. By reason of the fact that the eye bolt 16 has a swivel connection with 80 the bracket, it is obvious that subsequent to the elevation of the pipe and pump, these parts can be rotated in the proper direction together with the tubular member 10 and rod 17 for the purpose of uncoupling the 85 desired number of sections of the pipe and pump rod, without the tackle rope being twisted or tangled or in any way interfering with this operation. When the parts have been uncoupled, they can be easily and 90 quickly lowered to the ground with safety, and when rested upon the ground the tackle rope being slack permits the section or sections of the pipe and pump rod to be uncoupled from the device. It is of course understood that the tubular member 10 and rod 95 17 can be used in combination as hereinabove stated, but when it is desired only to elevate the pipe the rod 17 can be dispensed with as it is detachably associated with the 100 bracket.

It is believed that from the foregoing description the nature and advantages of the invention will be readily apparent without requiring a more extended explanation and 105 therefore the same has been omitted. However I desire to have it understood that I do not limit myself to the precise construc-

tion illustrated, and that various changes may be made when desired as fall within the scope of what is claimed.

What is claimed is:—

- 5 A device of the class described comprising a hollow tubular member exteriorly threaded at one end, a bracket arranged within said member, means for holding the parts operatively associated, an eye bolt
10 swiveled to the upper end of said bracket,

and a threaded rod depending from the opposite end of said bracket and detachably connected therewith.

In testimony whereof I affix my signature in presence of two witnesses.

SAMUEL H. WOLFE.
